UNITED STATES PATENT OFFICE

2,610,261

NEUTRALIZATION OF HIGH GAIN AMPLIFIERS

George D. Wofford, Towson, Md., assignor to
Bendix Aviation Corporation, Towson, Md., a
corporation of Delaware

Application May 23, 1947, Serial No. 749,986

2 Claims. (Cl. 179—171)

1 directed to vacuum tube
2 5 electrically it is directed to the
the regeneration in high gain
10 tubes, tetrode or pentode tubes.
15 increasing regeneration in high
15 particularly at high radio fre-
15 quency has long since been attacked from
20 the development of multielectrode
25 tubes with their low grid-plate
25 capacity. At the time to have solved the
30 problem of the development of tubes hav-
35 ing low grid-plate capacity, the
40 conductance and conse-
45 quence, however, has brought
50 the problem before again. Grid-plate
55 capacity, however, for
60 capacities are often suffi-
65 cient to sustain oscillation in mod-
70 eling of the amplifier,
75 as where the stray capaci-
80 ties may have an adverse
85 characteristic.
90 This invention to provide a
95 with a minimum of regen-
100 by the use of an impeder
105 screen electrode of an ampli-
110 fier in such a manner that a neutralizing
115 current is induced in the said screen.
120 Other objects and advantages
125 of the invention will more fully appear
130 from the detailed description when the
135 accompanying figures. Fig. 1 is the schematic dia-
140 gram incorporating the instant
145 modified version of the
150 circuit 14, resulting from feedback through
155 the small capacity between the anode and con-
160 trol grid of the pentode 10. According to the
165 invention, this component will be offset by a
170 positive resistive component resulting from feed-
175 back of the drop across resistor 13 through the
180 much larger capacity between screen and control
185 grid. The drop across the resistor 13 arises in
190 part from the flow of the modulated space cur-
195 rent through it and through the stray capacities
200 shunting it, and in part from that portion of the
205 circulating current of circuit 14 which flows
210 through it in series with the capacity of the
215 anode to the suppressor grid and cathode of the
220 pentode 10. The component of the drop across
225 resistor 13 which is in quadrature to the space
230 current produces the compensatory positive re-
235 sistive component of input impedance seen at
240 the terminals 11, while the inphase component
245 merely increases the apparent capacity seen
250 across the terminals. Since the phase of the
255 second named circulating part of the current
260 through the resistor 13 varies with frequency,
265 the positive resistive component of impedance
270 induced at the input terminals 11 also varies with
275 frequency. It has been experimentally deter-
280 mined that the net resistive component resulting
285 from the two feedback links may be made
290 negligible over the normal useful bandwidth of
295 circuit 14 by proper choice of the values of the
300 circuit elements such that substantially equal
305 and opposite resistive components of impedance
310 are induced across input terminals 11. In a typi-
315 cal amplifier operating at a frequency of about
320 460 kilocycles it has been found that optimum
325 conditions require the resistor 13 to be of the
330 order of 100 ohms.

In Fig. 2 there is illustrated an alternative arrangement of the Fig. 1 embodiment for use in circuits wherein it is desired to operate the screen electrode at a considerably lower voltage than that supplied to the anode circuit. Here the resistor 15 connected between the screen and the positive terminal of the source 12 acts as a series dropping resistor and the condenser 16 connected between the junction of the resistor 13 and the circuit 14 and the screen electrode provides a path to the screen for the feedback balancing signal.

50. What is claimed is:

1. In an amplifier of wave signal energy comprising a vacuum tube having at least a cathode, a control electrode, a screen electrode and an anode in the order as named; a source of screen and anode voltage for said tube, a tuned load

and a resistor serially connected between said anode and said source; said screen electrode being connected to the junction of said tuned load and said resistor so that said resistor is serially connected between said screen electrode and said source; and said source and resistor providing the path of lowest impedance between said screen grid and said cathode.

2. In an amplifier of wave signal energy comprising a vacuum tube having at least a cathode, a control electrode, a screen electrode and an anode in the order named; a source of screen and anode voltage for said tube; a tuned load and a resistor serially connected between said anode and said source; said screen electrode being connected to the junction of said tuned load and said resistor so that said resistor is serially connected between said screen electrode and said source; the value of said resistor being so selected that the voltage drop across it will reflect across the input of said amplifier a resistive component of impedance of such magnitude and sense as to neutralize the resistive com-

ponent of the input impedance thereof due to capacitive feedback to said control electrode from said anode; and said source and resistor providing the path of lowest impedance between said screen grid and said cathode.

GEORGE D. WOFFORD.
